WINDOW CONSTRUCTION

Benjamin H. Marcus, Brooklyn, N. Y.

Application September 23, 1944, Serial No. 555,577

3 Claims. (Cl. 20—53)

My invention relates to tilttable windows and more particularly to sash windows comprising vertically maintained lateral parts and a frame hinged in these parts.

Hinged windows are known which can be turned down into the room for convenient cleaning after the means interlocking the frame and the lateral parts have been released. It is, however, dangerous or undesirable if this release can be effected by everybody, for example, by children or incompetent persons who may break the pane or may damage the mechanism of the window or may fall out of the window by carelessness. Objects of my invention are to make the interlocking and releasing means fool-proof, to prevent these means from being operated inadvertently or by unauthorized persons, and to provide a stop for the release which can be removed only by a key.

Also windows are known which can be tilted into an oblique position adapted for ventilation. Such tilting does not involve the dangers mentioned before, and it is desirable that such tilting can be effected by handy and always ready means without the necessity of using a key. Therefore, other objects are to provide means interlocking the frame and the lateral parts in closed position of the window which means can be readily released as far as to permit the frame to assume an oblique position, but which are stopped from being released into a position permitting the frame to turn down completely.

Further objects are to provide means to secure a window in closed or in partly opened position, to use the same means for these two purposes, to make these means releasable in two steps, to operate these steps by the same handy means, and to provide a removable stop preventing one of these steps.

Another object is to use two separate lateral parts which are arranged slidably in vertical direction for a window of this structure.

Still other objects are to achieve these results with simple, inexpensive, effective and reliable means and with means that will not operate accidentally and that can be operated with a small force.

Still further objects and advantages will appear from the following description of an exemplifying embodiment of my invention, from the appended claims and from the accompanying drawing in which:

Fig. 1 shows a vertical elevation of a window embodying my invention, most parts being shown in a cross-section taken along the line 1—1 of Fig. 2 and seen from the lower side in Fig. 2, the

right side of the window being shown broken off.

Fig. 2 shows a horizontal cross-section of the same embodiment, taken along the line 2—2 in Fig. 1 and seen from the upper side.

Fig. 3 shows a vertical side view of the same embodiment seen from the left side in Figs. 1 and 2, the left lateral part being shown in a cross-section taken along the line 3—3 in Fig. 2, the frame being shown in an oblique position, a completely turned down position of the frame being indicated by dotted lines.

Fig. 4 shows a vertical cross-section of the upper ledge of the window, taken along the line 4—4 in Fig. 2 and represented on a larger scale.

Referring to the drawing, numeral 5 indicates the lateral parts, and 6 the frame or casement of the window. The parts 5 may be connected to a building in an opening thereof in any known and suitable manner, for example, stationarily or 20 slidably inserted between vertical rails 7. The frame 6 is hinged to the parts 5 preferably by two horizontal pivots 8 positioned near the lower edge of the frame. A glass pane 9 is inserted in the frame 6 in conventional manner. A lever arm 10 is hinged to the lateral part 5 by a horizontal pivot 11 and is positioned between this lateral part and the frame so that the arm 10 can turn in a plane perpendicular to the plane of the pane 9. Preferably, another identical lever arm 10 is 25 similarly positioned at the symmetrically opposite side of the window. The arms 10 have openings adapted to be engaged by bolts as will be described later. These openings may be formed, for example, by slots 12.

The upper part or ledge of the frame 6 is hollow and may be formed by an upper horizontal wall 13, a lower horizontal wall 14, an inner vertical wall 15 and an outer vertical wall 16. In the space surrounded by these walls, bodies 17 are positioned 30 slidably in a direction parallel to these walls. Preferably, one body 17 is arranged at each of the two ends of this space. The bodies 17 may have slots 18 through which bolts 19 and 20 affixed to the walls 13 and 14 pass. A bolt 21 is affixed to the outer end of each body 17 and projects therefrom in a lateral, horizontal direction. The inner end of each body 17 has a recess 22 in the bottom of which two steps are formed, one of these steps formed by a surface 23 and the other step by a surface 24 having a larger distance from the outer end of the body 17 than the surface 23.

The bodies 17 are permanently drawn to the outer sides, for example by coil springs 25 having inner ends affixed to pins 26 secured to the bodies 17 and having outer ends affixed to the bolts 19.

The bodies can be withdrawn to the inner sides against the action of the springs 25, preferably by flexible means acting simultaneously on both bodies. For example, a cord or chain 27 is affixed to each body 17, and these two chords are passed through openings 28 in the wall 14 and have ends hanging down and forming an united string 29 which can be easily pulled by a person standing on the floor of the room.

Stops are provided for the inward movement of the bodies 17 and may be formed by a member 30 having two arms extending into the recesses 22. When the bodies 17 are in their outer position, as shown in Figs. 1 and 2, these arms are spaced from the bottoms of these recesses. The member 30 is so movable or adjustable that it can act as a stop by contact with either the surfaces 23 or 24. This adjustment may be made, for example, by a turning movement of the member 30 which may be provided with pivots 31 passing through bores in the walls 13 and 14.

Preferably, the adjustment of the member 30 is made by means of a special key fitting a key hole 31a in the wall 15 and, after passing this key hole, engaging a recess 32 in the member 30 whereby the key 33 turning in a vertical plane turns the member 30 sufficiently in a horizontal plane.

When the window is closed, the bolts 21 pass through the slots 12 of the lever arms 10 and also engage holes 34 provided co-axially in the lateral parts 5 as shown in Figs. 1 and 2. In this position of the window, the arms 10 are positioned vertically and contact stops 35 affixed to the lateral parts 5. Ordinarily the member 30 remains permanently in the position shown in the same figures.

When a person pulls the string 29, the bodies 17 slide inwardly until the surfaces 24 contact the member 30 and, at the same time, the bolts 21 leave the holes 34 and thereby release the frame 6 which, eventually by a slight further pull on the string 29, will fall down into the oblique position shown in Fig. 3 in full lines. In this position, the bolts 21 contact the lower ends of the slots 12, and the arms 10 prevent further downfall of the frame 6. This position of the window is adapted for ventilation. The ventilation may be improved in conventional manner by a second window arranged below or above the first window and preferably constructed and operated in the same manner whereby these two obliquely positioned windows facilitate a circulating ventilation.

When the frame 6 is lifted again into its vertical position, the bolts 21 automatically engage the holes 34 and secure the frame in its original position.

In order to open the window completely or to bring it into a position convenient for cleaning, the key 33 is passed through the hole 31a into the recess 32 and then turned until the arms of the member 30 are in line with the surfaces 23. This can be done whether the window is closed as in Fig. 1 or partly open as in Fig. 3. When thereafter a person pulls the string 29, the bolts 21 move to the inner side sufficiently far as to leave the slots 12 of the lever arms 10 whereby the frame 6 is fully released and can be turned down into the position shown in Fig. 3 in dotted lines. At the same time, the lever arms 10 return into or remain in the vertical position shown in Fig. 3 in dotted lines.

The frame 6 may be supported in the lowered position and may be prevented from falling further down by suitable means, for example by arms 36 and 37. The arm 36 is rotatable around a

pivot 38 affixed to the lateral part 5. The arm 37 is rotatable around a pivot 39 affixed to the frame 6. The ends of these two arms opposite to these pivots are connected with each other by a pivot 40. When the window is closed the arms 36 and 37 are folded into parallel position. Similar arms 36 and 37 may be provided at the other side of the frame.

In order to secure the window again in closed position, it is only necessary to raise the frame 6 until the window is shut, pulling the string 29. Then, upon release of the string, the bolts 21 return automatically into the original interlocking position. Then, the key 33 may be used to turn the member 30 into its original position.

I desire it understood that my invention is not confined to the particular embodiment shown and described, the same being merely illustrative, and that my invention may be carried out in other ways without departing from the spirit of my invention as it is obvious that the embodiment shown and described is only one of the many that may be employed to attain the objects of my invention.

Having described the nature of my invention and how it operates, what I claim and desire to secure by Letters Patent is:

1. In a window having two lateral parts and a frame hinged to said lateral parts, means for securing said frame to said lateral parts releasably in two different positions, said means comprising a body slidable in said frame and having two surfaces forming steps spaced in the sliding direction at one side of said body, a bolt affixed to said body at the opposite side, an arm hinged to one of said lateral parts and having a slot engageable by said bolt, said lateral part having a hole engageable by said bolt and positioned beyond said arm seen from said body in the sliding direction, a spring drawing said bolt into said engagements, means to withdraw said bolt from said engagements, a member movably connected to said frame and having a surface acting as a stop for the withdrawal of said bolt by contact with either of said two surfaces of said body, and means to move said member from a position stopping one of said surfaces of said body into a position stopping the other of said surfaces.

2. In a window having two lateral parts and a frame hinged to said lateral parts, means for securing said frame to said lateral parts releasably in two different positions, said means comprising a body slidable in said frame and having two surfaces forming steps spaced in the sliding direction at one side of said body, a bolt affixed to said body at the opposite side, an arm hinged to one of said lateral parts and having a slot engageable by said bolt, said lateral part having a hole engageable by said bolt and positioned beyond said arm seen from said body in the sliding direction, a spring drawing said bolt into said engagements, means to withdraw said bolt from said engagements, a member movably connected to said frame and having a surface acting as a stop for the withdrawal of said bolt by contact with either of said two surfaces of said body, and a removable key engaging said member and thereby moving said member from a position stopping one of said surfaces of said body into a position stopping the other of said surfaces.

3. In a window having two lateral parts and a frame hinged to said lateral parts, means for securing said frame to said lateral parts releasably in two different positions, said means comprising a body slidable in said frame and having

two surfaces forming steps spaced in the sliding direction at one side of said body, a bolt affixed to said body at the opposite side, an arm hinged to one of said lateral parts and having a slot engageable by said bolt, said lateral part having a hole engageable by said bolt and positioned beyond said arm seen from said body in the sliding direction, a spring affixed to said body and to said frame and drawing said bolt into said engagements, flexible means affixed to said body and 10

adapted to withdraw said bolt from said engagements, a member movably connected to said frame and having a surface acting as a stop for the withdrawal of said bolt by contact with either of said surfaces of said body, and a removable key engaging said member and thereby moving said member from a position stopping one of said surfaces of said body into a position stopping the other of said surfaces.
